LUDWIG KREUZINGER, OF CAMBRIDGE, ASSIGNOR TO THE METALLIC COMPRESSION CASTING COMPANY, OF BOSTON, MASSACHUSETTS, ASSIGNOR TO RUSSELL & ERWIN MANUFACTURING COMPANY, OF NEW BRITAIN, CONNECTICUT.

Design No. 4,105, dated June 7, 1870.

DESIGN FOR AN ESCUTCHEON.

The Schedule referred to in these Letters Patent and making part of the same.

I, LUDWIG KREUZINGER, of Cambridge, in the county of Middlesex and State of Massachusetts, have invented and produced a new and original Design for an Escutcheon, of which the following is a specification.

The nature of my design is represented in the accompanying photographic illustration, to which reference is made.

I claim the design for an escutcheon, substantially as above set forth.

LUDWIG KREUZINGER.
